DESIGN FOR A TABLE

William H. McDonald, Bloomington, Ind., assignor to The Nurre Companies, Inc., Bloomington, Ind., a corporation of Indiana

Application March 10, 1944, Serial No. 112,852

Term of patent 3½ years

(Cl. D33—14)

To all whom it may concern:

Be it known that I, William H. McDonald, a citizen of the United States and a resident of Bloomington, in the county of Monroe and State of Indiana, have invented a new, original, and ornamental Design for a Table, of which the following is a specification, reference being had to the accompanying drawing, forming a part thereof, wherein:

Figure 1 is a perspective view of a table, showing my new design; and

Figure 2 is a side elevational view thereof.
A characteristic feature of my design as shown

in the accompanying drawing is the provision of a single panel glass top for the table having contrasting transparent and mirrored areas, the transparent area forming the central part of the table top and the upper extremities of the supporting legs for the table terminating beneath and being concealed by the mirrored area of the glass top.

I claim:

The ornamental design for a table, as shown and described.

WILLIAM H. McDONALD.
